GEORGE HADFIELD, OF CINCINNATI, OHIO.

Letters Patent No. 60,883, dated January 1, 1867.

IMPROVEMENT IN MEDICAL VACUUM APPARATUS.

The Schedule referred to in these Letters Patent and making part of the same.

TO WHOM IT MAY CONCERN:

Be it known that I, GEORGE HADFIELD, of Cincinnati, Hamilton county, Ohio, have invented a new and useful Improvement in Medical Vacuum Apparatus; and I hereby declare the following to be a full, clear, and exact description thereof, reference being had to the accompanying drawings, making part of this specification.

This is an improvement in the class of devices employed by physicians to temporarily relieve a limb or other large portion of the human body from atmospheric pressure; and consists, first, in a construction of the receiver or vacuum chamber which facilitates its use with paralytic and other infirm persons, and which also enables it to be readily transported from place to place; and secondly, in the provision of a peculiarly formed air-tight cloak, adapted to entirely envelop the receiver proper and head of the patient; and my invention especially relates to such medical vacuum chambers as are designed for application to the entire person, the head excepted.

Figure 1 represents my receiver in its open condition to receive the patient.

Figure 2 shows the same closed and in condition for use.

The receiver proper consists essentially of a base, A, which may be of circular or oval form, and two conoidal shells or sides, B C, of which one side, B, is permanently attached to and forms one piece with the base, while the other side, C, is hinged, c, to the fixed side B, so that it can be opened therefrom, as seen in fig. 1, so as to enable the patient to easily enter or be conducted into the receiver on the ground level. That portion of the shells B C nearest to the back of the patient rises vertically or almost vertically upward, and curves abruptly forward as it approaches the top, while the opposite portion curves rearward from the base. The shells B C have semicircular openings, F F', which, in the closed condition, unite to constitute a round orifice that encircles the neck of the patient and permits the head to remain outside, as seen in fig. 2. The dimensions and form of the shells are designed to conveniently accommodate the patient in a sitting position with economy of material and the greatest practicable restriction of the internal capacity of chamber to be exhausted. The base A is surrounded by a groove, D, for a purpose that will presently appear. Casters, E, may be provided on the under side of the base to enable the apparatus to be readily shifted from place to place. The receiver proper may be formed of any suitable material, but my practice has been to make the base of wood and the sides of tinned or zinced sheet iron, stiffened by ribs of the same material. The patient may be supported on any convenient chair or stool, which may be either separate or be permanently secured to the base, and such chair may have its seat capable of vertical adjustment, as seen in fig. 1. G is a pipe which extends from the interior of the receiver quite through the base, and connects by flexible tube, H, or otherwise, with the suction of an air-pump. This pipe may have a cock, I, to open and close communication with the air-pump, and a cock, J, to admit air from the outside, so as partially or wholly to restore the atmospheric pressure within the receiver. In order to effectually exclude the external air, independently of any tightness of the joints of the receiver, I provide a peculiarly formed cloak, L, of India rubber or other flexible and impervious material, so shaped as to snugly envelope the receiver. The skirt of this cloak is held tightly to the grooved periphery of the base by means of an elastic cord or band, M. The cloak L is surmounted by a hood or cap, N, which snugly envelops the head of the patient, and has an aperture, n, that leaves the face and breathing organs free.

I have selected to illustrate my invention a form approved by actual use, but reserve the privilege of obtaining the same results by any means substantially equivalent; for example, both shells may be removable and may rest each one independently upon the base, and an elastic band may be applied around the cap or hood for more effectual exclusion of the air, while on the other hand the separate band M may be dispensed with by making the skirt of the cloak sufficiently elastic to tightly grasp the periphery of the base.

I am aware that the practice of relieving portions of the human body from atmospheric pressure in the treatment of diseases is of many years' standing, but the appliances heretofore proposed, especially when designed for the body proper or trunk, have been of limited practicability, because too bulky to be moved from place to place, or too difficult of access for paralytics and other crippled and disabled persons. I therefore disclaim the invention of such appliances apart from my specific improvements; but I claim herein as new and of my invention—

1. The medical vacuum chamber or receiver, composed of several separable parts, A, B, and C, so as to be

accessible from the ground level; in the described combination with an impervious and flexible envelope, L N, adapted to tightly invest the receiver and the head of the patient, substantially as set forth.

2. The receiver proper, consisting of the circumferentially grooved base A, through which the exhaust tube passes; a side portion, B, fixed to said base, and a movable side portion, C, hinged to the fixed side, as described.

3. In the described combination, I claim the circumferentially grooved base A and elastic band M, for securing the lower edge of the cloak or envelope, as set forth.

4. The flexible air-tight envelope, consisting of the cloak L, cap or hood N, and elastic band M, for the purpose explained.

In testimony of which invention I hereunto set my hand.

GEORGE HADFIELD.
